Patented Jan. 29, 1833.

Case 1.

Alpheus Stote.

Letters Patent.

The Schedule referred to in these Letters Patent and making part of the same, containing a description in the words of the said Alpheus Stote himself, of his improvement, in the anthracite coal stove, by closing the ash-pit, illuminating the front, and transferring the door to the top thereof.

Case No. 1.

Specification of improvements made in the anthracite coal stove by illuminating its front, transferring the door to the top, and enclosing the ash-pit. Whereas inconvenience has arisen in said stove from the invisibility of the fire, and the want of an opening at the top for the admission of fuel and the use of the poker, as well as from the diffusion of ashes and the ingress of cold air from the ash-pit. Therefore certain improvements have been attempted, and the same having been tested and perfected by repeated experiments are now intended to be introduced into general use; which improvements consist, in combining a vertical front grate and an exterior ash containing laminated glass or other transparent material, the same being constructed and adjusted in place ashore before in any manner prepared, with an opening at top, governed by a door or lid, for putting in the fuel & using the poker; and also if desired, with a closed ash-pit having its inlet for air governed by a valve or an ash drawer operating as a valve. For further information, reference may be had to the drawings and explanations thereto subjoined. Summary. The improvement herein contemplated consists in combining in one anthracite coal stove, a vertical front grate and a dash exterior thereto containing laminated glass or other transparent material with an opening at top, governed by a door or lid for the admission of fuel.

The use of the poker; and also of a valve with a closed air-pot having its outlet for air governed by a valve or valve device, operating as a valve. I therefore claim as my invention improvement the illuminating of the front of an automobile and other and the burning of a crop thence vertically, for the purpose of fuel and the use of the poker, by combining in front a vertical pipe and an obtuse end forming a valve or valve device, with an opening at the governed by a valve, and this whether the closed air-pot with its outlet for air governed by a valve, or a valve device, operating as a valve, be added to the foregoing combinations or not, though such addition is preferred together with the uses to which said combination has been or may be applied.
